UNITED STATES PATENT OFFICE.

WILLIAM R. BAKER, OF CHICAGO, ILLINOIS, ASSIGNOR TO THE McCORMICK HARVESTING MACHINE COMPANY, OF SAME PLACE.

MOWER.

SPECIFICATION forming part of Letters Patent No. 361,607, dated April 19, 1887.

Application filed March 12, 1885. Serial No. 158,625. (No model.)

To all whom it may concern:

Be it known that I, WILLIAM R. BAKER, a citizen of the United States, residing at Chicago, in the county of Cook and State of Illinois, have invented certain new and useful Improvements in Mowers, of which the following is a specification.

My invention relates to that class of mowers known as "two-wheel hinge-bar front-cut machines" in which there is a floating and rocking finger-bar connected to the main frame by a coupling-frame and thrust-bar; and it consists in hinging the coupling-arm and the thrust-bar to the main frame between the carrying-wheels upon diagonal pivots arranged upon the same axis with the rear pivot in close proximity to the axle; in combining with the coupling-arm and thrust-bar, both hinged upon a common diagonal axis, and with the finger-bar a tilting lever having its weight-arm substantially in line with said axis, in order that the rising and falling of the finger-bar may not essentially affect the adjustment of the cutter-bar; in a hollow coupling-frame forked at its end to embrace the inner shoe of the finger-bar and having a recurved head on the rear arm of the fork and a vertical shielded guideway in the front arm; in combining with the forked coupling-arm a thrust-bar pivoted to the main frame upon the same diagonal hinge with said coupling-frame and bolted rigidly to a seat upon the rear arm of the fork; in combining with a wing or spur on the front arm of the forked coupling a lead-wheel receiving the point of said wing within its re-enteringly-curved rim, to act as a rolling shoe or inside divider, and in various other details of structure, hereinafter described and claimed.

In the drawings, Figure 1 is a top plan view of a mower embodying my invention, the tongue and finger-bar being partly broken away. Fig. 2 is an elevation thereof from the divider side. Fig. 2^a is a detail showing the fore part of the coupling-fork and inner shoe and the connection between the two. Fig. 3 is an enlarged detail in section of the lead-wheel and the connection between it and the coupling-arm; Figs. 4 and 5, enlarged details showing the arrangement of the inner shoe

and rear arm of the forked coupling, and the lever and tilting chain with its bell-crank.

A represents the main or driving wheels of the machine; B, the main frame with incased gearing; C, the driver's seat; D, the draft tongue, and E the cutter crank-shaft, the arrangement of these being such as usual in mowers now in the market, and not requiring further description.

To the bracket e, which shields the connection between the pitman and wrist-pin, and in front thereof, I hinge on a diagonal pivot-pin, f, directed inward toward the axle and inner wheel, a coupling-arm, F, which may be of the usual form, but which, for lightness and increased strength, I prefer to make as shown— that is, it is cast hollow, in one piece of gradually-enlarging diameter toward the inner shoe, and near its free end is forked or provided with an offsetting arm, F', which extends rearwardly at right angles to the main arm, for the purpose of supporting various parts, as hereinafter explained, until it reaches and passes slightly beyond the heel of the inner shoe, when it curves upon itself and terminates in a spherical head or ball, f', to form one member of a universal coupling with the inner shoe. Directly in front of this ball the extended main arm has a vertical recess or way, f'', formed in said arm and in a downward offset from the same, and closed or shielded at top and bottom, as well as at the sides.

A thrust-bar, G, is rigidly bolted to a seat formed upon the rear end of the arm F', and is hinged to the main frame just beneath the axle by a diagonal pivot, g, in line with or upon the same axis as the pin, by which the coupling-arm is hinged, the purpose of these diagonal pivots being to keep the finger-bar in line, notwithstanding its flexions, and also to more effectually resist the leverage of the finger-bar.

In front of the coupling-arm and integral therewith, or rigidly affixed thereto, is a wing, g', flaring outwardly and forwardly and terminating in a point or spur. A vertical slotted elongated boss, g'', upon this wing receives a bolt, g', securing thereto a tubular stub-axle, g', supporting the lead-wheel H, which is thus

made to carry the weight of the coupling-arm and parts which it supports, and which may be adjusted up and down along the slotted boss to change the height of the inner end of the 5 finger-bar. This lead-wheel is hollow, and is open on one side, except, as shown in Fig. 3, for a re-entrant rim, h , which forms an angular chamber, h' , within the tread. Into this chamber the point or spur of the wing-piece projects, coming close to the edge of the rim and being entirely shielded thereby, so that the wheel and the wing-piece together form in effect both an inner divider and a rolling-shoe.

The inner shoe, I, has at its rear or at its 15 wheel end a spherical socket, i , for the reception of the ball in the rear fork of the coupling-arm, and on its toe an anti-friction roller, i' , which is received into and fits snugly within the shielded recess or way in the front fork. 20 Behind this it is curved to substantially follow the curved outline of the tread of the lead-wheel, and merges into the finger-bar K practically on a line with the inner face of said wheel.

25 To the inner or divider side of the rear fork of the coupling-arm is pivoted a bell-crank lever, L, one arm, l , of which connects by a short chain, l' , with the front part of the shoe, so as to lift it within its guideway, thus tilting the 30 finger-bar, and yet permitting it to be further lifted by any sinuosity of the ground or by any obstruction. The other arm, l'' , of the bell-crank is connected by a link, l'' , with a lever, M, pivoted at the rear of the axle and having the usual segment-rack, m , and detent. The 35 location of this lever is such as to bring its lower or weight arm substantially in line with the diagonal axis of the coupling-arm and thrust-bar, so that the tilting adjustment of the finger-bar will be practically undisturbed by flexions or movements of the floating or coupling frame formed by the coupling-arm and thrust-bar. On the other side of the rear fork and beneath the thrust-bar is pivoted a 40 gag-lever, N, the lower arm of which comes against a lateral spur, n , from the heel of the inner shoe, and the other arm has a socket, n' , in which the thrust-bar is received, and is connected by a chain, n'' , with the lifting-segment 45 and actuating-lever O on the main frame, so that whenever this actuating-lever is moved to take in the chain the gag-lever will first act upon the finger-bar to lift its outer end, and will then, if the movement of the lever is continued, catch upon the thrust-bar and lift the 50 finger-bar and floating frame bodily.

In order to lighten the draft or pressure of the floating frame upon the ground, a stirrup, P, is hinged to the draft-tongue, and to this 55 is attached the clip p , for the double-tree. A link, p' , connects this stirrup with the thrust-bar about opposite the tread of the carrying-wheel, so that as the stirrup is rocked by the draft of the team the link will draw upon the 60 thrust-bar and tend to raise it and the parts to which it is rigidly attached, or which, by

means of the gag-lever, are so locked to the others as to be compelled to follow their movements.

I am aware that in Letters Patent granted 70 to J. B. Kershaw, June 15, 1869, No. 91,347, a ball-joint is shown between the finger-bar and coupling-frame at the heel of the inner shoe; but in such joint the ball is upon the shoe and the socket upon the rear fork of the coupling-frame, so that it is directed forward, and is 75 peculiarly liable to catch and collect the fine gritty dust that is stirred up from the stalks and stubble in the passage of the machine, thus causing the joint to clog and grind, wearing it out rapidly. In my machine, on the contrary, the socket, being upon the heel of the shoe, has its mouth directed to the rear, and thus serves the twofold function of member of the joint and shield therefor. 80

I claim—

1. The combination, substantially as hereinbefore set forth, in a two-wheel hinge-bar front-cut mower, of a main frame and a coupling-frame hinged thereto between the carrying-wheels by diagonal pivots arranged upon the same axis, and the rear pivot being adjacent to and beneath the axle. 85

2. The combination, substantially as hereinbefore set forth, in a two-wheel hinge-bar front-cut mower, of a main frame, a coupling-arm hinged thereto by a diagonal pivot, and a thrust-bar hinged also to the main frame close to the axle by a diagonal pivot on the same axis as the pivot of the coupling-arm, 90 both pivots being within the carrying-wheels. 100

3. The combination, substantially as hereinbefore set forth, in a two-wheel hinge-bar front-cut mower, of the main frame, the forked coupling-arm hinged thereto by a diagonal pivot, the tilting or rocking finger-bar carried by said coupling-arm, and the thrust-bar rigidly secured to the rear fork of the coupling-arm and hinged to the main frame by a diagonal pivot in continuation of the other. 105

4. The combination, substantially as hereinbefore set forth, of the hollow forked coupling-arm having a spherical forwardly-projecting head on the rear fork and a vertical shielded recess in the front fork, and the inner shoe having a spherical socket engaging with said head and an anti-friction roller on its toe entering in and playing within said recess. 110

5. The combination, substantially as hereinbefore set forth, of the wing-piece and the lead-wheel having a re-entering rim which embraces and shields the point of said wing-piece. 120

6. The combination, substantially as hereinbefore set forth, of the coupling-arm, its wing-piece, and the lead-wheel turning on a stub-axle from said wing-piece and having a re-entering rim which embraces and shields the point thereof. 125

7. The combination, substantially as hereinbefore set forth, of the forked coupling-arm, 130

its diagonal hinge, the thrust-bar and its diagonal hinge, and the tilting-lever having its link-arm arranged substantially in line with the axis of said diagonal hinges.

5 8. The combination, substantially as hereinbefore set forth, of the forked coupling-arm hinged to the main frame by a diagonal pivot-pin, the inner shoe hinged to the rear fork of said coupling-arm and playing, as to its toe, 10 in a vertical recess in the front fork, the thrust-bar, also hinged to the main frame by a diagonal pivot-pin in line with the first, the bell-crank pivoted to the rear fork and connected by chain-links with the front of the 15 shoe, the tilting lever from the main frame having its link-arm substantially in line with the diagonal pivots, and the link connecting the bell-crank with said link-arm.

9. The combination, substantially as hereinbefore set forth, of the forked coupling-arm, 20 the inner shoe connected with the rear fork by a hinge-joint and controlled at its toe by a vertical guide or recess in the front fork, the thrust-bar bolted to said rear fork, the gag-lever pivoted to the rear fork and having a 25 socket for the reception of the thrust-bar, the lateral spur from the heel of the shoe with which the lower arm of the gag-lever engages, and the lever upon the main frame connected 30 with the upper arm of the gag-lever.

10. The combination, substantially as hereinbefore set forth, of the forked coupling-arm, 35 its forwardly-projecting wing-piece, the lead-wheel supported on a stub-axle from said wing-piece and embracing and shielding its point, and the inner shoe hinged to the rear fork by a universal joint and having its toe restrained and guided by the vertical recess in the front fork and shielded on its inner side by said lead-wheel.

40 11. The hollow forked coupling-frame constructed, substantially as described, of a single casting with rearwardly-extending arm terminating in a recurved spherical head, and with vertical shielded guideway in the front arm.

12. The hollow forked coupling-frame formed as a single casting, having the rear member of the fork arranged at right angles to the other and inwardly curved at its end 50 and terminating in a spherical head, and the forward member provided with a vertical guideway for the toe of the shoe and with a forwardly-extending wing-piece, substantially as described.
